UNITED STATES PATENT OFFICE.

JOHN H. BROWN, OF NEW YORK, N. Y.

GUN.

SPECIFICATION forming part of Letters Patent No. 496,637, dated May 2, 1893.

Application filed July 7, 1891. Renewed August 26, 1892. Serial No. 444,174. (No model.)

To all whom it may concern:

Be it known that I, JOHN H. BROWN, of the city and county of New York, in the State of New York, have invented a new and useful

5 Improvement in Guns, of which the following is a specification.

My invention relates to an improvement in guns and more particularly to a gun having a segmental core surrounded by a wire jacket. 10 Because of the increased strain at the breech of the gun and its gradual diminution as the muzzle is approached, the walls of the gun are made thicker at the breech than at the muzzle and the gun ordinarily presents a gradual taper 15 per cent from the breech toward the muzzle.

In providing a core with a wire jacket, particularly where the jacket is relied upon to withstand the explosive strain of the charge, it is a matter of economy to stop successive 20 layers of wire at different distances from the muzzle, so as to give the necessary tension at the breech and gradually diminish such tension as the explosive strain is diminished toward the muzzle.

25 Great difficulty has been found in successfully anchoring the ends of the different shorter layers of wire when terminated intermediate of the ends of the preceding layer, and it is to provide a gun which shall overcome such difficulty and present a smooth exterior finish that I have devised the present structure.

In constructing the gun, I provide a seat for the short layer having the true taper of 30 the gun, and terminated toward the muzzle end by an abutment, then wind the short layer and anchor its end between the last coil and the abutment, then provide a seat for the extended portion of the next succeeding 35 layer forming a prolongation of the surface of the preceding layer, wind the second layer and anchor its end, and so proceed until the full length layer is reached.

The accompanying drawings illustrate the 40 invention.

Figure 1 shows the core in side elevation with seats for the short layers prepared and the first layer nearly completed. Fig. 2 is a

similar view showing the second layer completed, and, Fig. 3 is a longitudinal section of 50 the gun as it appears when the jacket is completed.

A represents the core, B and b the breech and muzzle nuts respectively, and a a', &c., the seats for the short layers, the said seats 55 terminating toward the muzzle in abutments c c', &c. The layer of wire constituting the short coil is represented by D, the next succeeding layer by D' and its anchored end by d'.

When the core is composed of several longitudinal segments as herein represented, they may be held in assembled adjustment for the reception of the jacket, by means of the breech and muzzle nuts B and b, and in 60 addition to these by bands of metal shrunk thereon intermediate of the breech and muzzle nuts, which bands may be turned off together with the faces of the segments in forming the successive seats a a', &c., for the reception of the several short layers. In cases 65 then where such intermediate temporary binding of the segments is found advisable, it will be expedient to form the seats a a', &c., by first forming the seat a, then winding the 70 layer thereon, then forming the seat a', then winding the layer D', &c., so that the segments will at no time be relieved of the necessary binding force to hold them in proper 75 position. This specific method of procedure 80 has the further advantage of enabling the operator to set his tool to the surface of the preceding coil, to cut the next succeeding seat. As the final coil of the layer is laid in 85 engagement with the abutment, as soon as it begins to ride on the edge of the preceding coil, the speed of winding may be reduced and the end may be driven into the gradually narrowing space between the abutment and previous coil, and thereby securely anchored, without slackening the tension or 90 disturbing the smooth continuous plane of the surface of the layer. When the distance between the breech and muzzle nuts is short or when for other reasons there is no need of 95 temporary binders between the nuts, the sev-

eral seats $a a'$, &c., may be formed successively and the winding be done after the several seats have been formed.

What I claim is—

5 A gun having its core or body provided on its exterior with a succession of seats separated by abutments and having the taper of the gun and layers of wire wound on said

seats, an outer or longer layer of wire being arranged continuously over a shorter inner layer and over the taper seat adjacent thereto, substantially as set forth.

JOHN H. BROWN.
